UNITED STATES PATENT OFFICE.

WILLIAM A. CROSS, OF CHICAGO, ILLINOIS.

WAREHOUSE-DOOR.

SPECIFICATION forming part of Letters Patent No. 663,219, dated December 4, 1900.

Application filed December 26, 1899. Serial No. 741,519. (No model.)

To all whom it may concern:

Be it known that I, WILLIAM A. CROSS, a citizen of the United States, residing at Chicago, in the county of Cook and State of Illinois, have invented certain new and useful Improvements in Warehouse-Doors; and I do hereby declare the following to be a full, clear, and exact description of the same, reference being had to the accompanying drawings, forming a part of this specification.

The present invention relates to hinged doors or gates for elevator-hatchways and for like uses.

The object of the present improvement is to provide a simple and efficient sectional and counterbalanced door for freight-elevator doorways and analogous uses adapted to be hinged at its top to the door-frame and capable of easy and convenient manipulation to open and close the doorway to which it is applied, all as will hereinafter more fully appear and be more particularly pointed out in the claims. I attain such objects by the construction and arrangement of parts illustrated in the accompanying drawings, in which—

Figure 1 is a perspective view of the present sectional door, its closed position being shown in full lines and its open position in dotted lines; Fig. 2, a vertical transverse section of the door and doorway, illustrating the door in a closed position; Fig. 3, a similar view with the door in an open or raised position; Fig. 4, a fragmentary front elevation of the door and connections; Fig. 5, an enlarged detail horizontal section through a lower corner of the door, illustrating the guide and guide-roller therefor; Fig. 6, a detail perspective view of a modified form of the hinge connection between the top of the door and door-frame.

Similar numerals of reference indicate like parts in the several views.

Referring to the drawings, 1 represents the wall of the building, 2 the opening or doorway therein, and 3 vertical guides or slide-ways at the sides of the doorway, which in my preferred construction, as illustrated in the drawings, are formed by sections of channel-iron.

In the present improvement the door comprises an upper and a lower section 4 and 5,

hinged together in any suitable manner at their meeting edges, and the door as a whole is in turn, hinged at top to the wall or door-frame by any ordinary hinge mechanism, either by butt-hinges, as shown in Figs. 1, 2, 3, and 4, or by a rod-shaped pintle, as illustrated in Fig. 6.

6 indicates combined guide and pivot blocks connected to the lower ends of the lower section 5 of the door by means of pivot-pintles 7. In the present construction the blocks 6 are adapted to move in the vertical guide-grooves of the stationary guides 2 and confine the extreme lower end of the door to a movement in a vertical plane.

8 indicates counterbalance cords or chains secured at one end to the guide-blocks 6 or to the pintle-pins 7, as may be found most convenient, and arranged to pass over elevated pulleys 9, their other ends being connected to the counterbalance-weights 10. By means of this construction the weight of the door is counterbalanced and the operation of the door to an open or closed position rendered both easy and convenient.

When desired, the counterbalance-weights 10 may be housed in vertical wells 11, as shown by dotted lines in Fig. 5, and arranged in parallel and adjacent relation with the vertical guides 2. Such provision may be dispensed with in ordinary warehouse constructions.

12 and 13 are handles or hasps secured to the lower section 5 of the door to afford convenient means for manipulating the door to a closed or open position.

14 is a transverse closing-strip secured across the seam between the upper and lower door-sections 4 and 5 for the purpose of affording a closed joint at such seam.

In the operation of the present invention to effect an opening of the door the operator will pull upon the upper hasp 12 to draw the central part of the door toward him, after which, by means of both upper and lower hasps, the door-sections can be moved into the open position illustrated in Fig. 3, the counterbalance-weights 10 aiding materially in the easy performance of the operation. In effecting a closure of the door a reversal of the above-described operations is performed, the operator drawing down the lower

end of the door by means of the lower hasp 13, and finally adjusting the door-sections to the position illustrated in Fig. 2 by both hasps.

Having thus fully described my said invention, what I claim as new, and desire to secure by Letters Patent, is—

1. The combination of a door frame or way, vertical slideways at the side of the same, a door hinged at top to the door-frame and formed by upper and lower sections of substantially equal size hinged together, guides for engaging the lower ends of the lower door-section with the slideways, and means for counterbalancing the weight of the door, substantially as set forth.

2. The combination of a door frame or way, sections of channel-iron secured to the sides of the same and constituting slideways, a door hinged at top to the door-frame and formed by upper and lower sections of substantially equal size hinged together, and guide-pintles on the lower end of the lower

door-section engaging in the vertical grooves of the slideways, substantially as set forth.

3. The combination of a door frame or way, sections of channel-iron secured to the side of the same and constituting slideways, a door hinged at top to the door-frame and formed by upper and lower sections of substantially equal size hinged together, guide-pintles on the lower end of the lower door-section engaging in the vertical grooves of the slideways, and flexible connections passing over elevated pulleys and connected at one end to a counterbalance-weight and at the other to the lower end of the lower door-section, substantially as set forth.

Signed by me at Chicago, Illinois, this 21st day of December, 1899.

WILLIAM A. CROSS.
